UNITED STATES PATENT OFFICE.

LILLIAN C. WHITTLESEY, OF WASHINGTON, DISTRICT OF COLUMBIA.

DEVICE FOR EXHIBITING COINS, &c.

SPECIFICATION forming part of Letters Patent No. 638,785, dated December 12, 1899.

Application filed March 3, 1899. Serial No. 707,659. (No model.)

To all whom it may concern:

Be it known that I, LILLIAN CAMP WHITTLESEY, a citizen of the United States, residing at Washington, in the District of Columbia, have 5 invented certain new and useful Improvements in Devices for Exhibiting Coins and the Like; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 The invention relates to means for displaying disk-shaped objects of value or interest, and especially souvenir coins, medals, and the like. It frequently happens that one has a rare or curious coin or similar article 20 which would be an attractive ornament for the mantel or the table if it were possible to display it properly without risk of its being brushed aside or covered up by papers or other things. So, too, on anniversaries of 25 days, weddings, and other "red-letter days" a pretty gift is some coins bearing appropriate dates, provided they can be displayed attractively. My invention aims to accomplish these and other objects in a simple and yet 30 effective manner.

The invention consists, essentially, in a holder constructed as hereinafter described, and particularly pointed out in the claims.

The holder has a groove or space to receive 35 the edge of the coin and is adapted to be bent to retain the coin in the groove. One holder can be used alone when a single coin is to be displayed, or two or more holders can be grouped in various ways to form useful and 40 ornamental articles, as hereinafter set forth. The coin, medal, or the like is held by its beaded rim only along a short arc, so that practically the entire coin is visible and its inscriptions and ornamentation on obverse, 45 reverse, and periphery can be examined and studied with ease.

In the accompanying drawings, forming a part of this specification, Figure 1 shows a single holder of simple construction. Fig. 2 50 is a vertical cross-section of the same. Fig. 3 shows two holders forming a pen-rack or

knife-rest. Fig. 4 shows a group of holders forming a letter-rack. Fig. 5 shows two multiple holders constituting a rack, and Fig. 6 shows four multiple holders grouped to make 55 a picture-frame.

The holder is composed of a body A and a base B, on which the body is supported. The body and base may be integral; but they are preferably made in separate parts fastened 60 together. A simple form of body is shown in Figs. 1 and 2, where it is composed of a short flat tube of suitable material, such as sheet metal, having upright walls, preferably parallel, and an open top. In width it corresponds 65 with the thickness of the coin to be held. In length it equals the chord of a small arc on the circumference of the coin. In depth it may vary to suit the circumstances.

The upper end of the holder is flat and has 70 an intermediate cut-away portion or notch, as at a, preferably on a curve concentric with but on a smaller radius than the circumference of the coin. When a coin C is inserted edgewise into this holder, the sides a' of the tube receive 75 it and hold it in an upright position. Means are provided for retaining the coin in place. Preferably this is accomplished by bending inward the corners a² of the notch or the entire flange formed by the edge of the 80 notch, so that the milled rim of the coin will be engaged by the said corners or flange, as indicated in Fig. 2. As the periphery of the coin rests against the upper end of the holder at a³, it will be seen that the coin is firmly secured 85 against accidental displacement. This mode of securing it avoids any risk of defacing the coin, yet at the same time it permits a ready removal of it when desired. These or any other equivalent form of single holder 90 may be grouped in various ways to make useful and ornamental articles.

In Fig. 3 two holders like those shown in Figs. 1 and 2 are united by a transverse member or bar G, thereby forming a convenient 95 knife-rest or pen-rack. This is an arrangement especially suited for displaying two coins commemorating an anniversary, such as a silver wedding, the coins selected being those having the appropriate dates, as "1874-100 1899."

Fig. 4 shows a series of holders united by

a transverse member or base H and adapted to hold a row of coins face to face. Such a device may be used as a letter-rack.

Instead of one holder I may make two or 5 more in the same body. Such a multiple holder is shown in Fig. 5, where two of them are connected by transverse members I to form a pen-rack. In this form the coins may be arranged to touch edge to edge, if so desired.

In Fig. 6 two parallel multiple holders are connected by transverse members which are themselves multiple holders, showing how a picture-frame can be formed. Such an article makes a pretty gift for a young person, the holders being filled with bright new pennies or dimes whose dates correspond with the successive years of the life of the recipient.

Multiple holders of this sort can be used by 20 numismatists to display collections of coins. Many other ornamental and useful articles can be devised by grouping these or equivalent holders.

I am aware that it has been proposed to construct a holder for plaques in which a base 25 is provided with a groove to receive the edge of the plaque and a clamp is arranged to hook over the opposite edge of the plaque to keep it from falling out of the groove; but in my 30 device the clamp is dispensed with and the coin is securely retained in the holder by bending or otherwise engaging the flanges of the holder with the milled rim of the coin. This prevents the coin from falling out of the 35 holder, and, indeed, it cannot be removed therefrom until the flanges are bent back or otherwise disengaged from the thickened rim.

Having thus described my invention, what I claim, and desire to secure by Letters Patent, is—

1. A device for displaying coins and the like,

consisting of two short parallel sheet-metal tubes, whose width is the same as the thickness of a coin, said tubes being adapted to receive a coin edgewise and provided with circular notches in their parallel walls concentric with but of smaller radius than the coin, and a bar connecting said tubes transverse to their length, substantially as described. 45

2. A device for displaying coins and the like, 50 consisting of two flat tubular sheet-metal holders, whose width is the same as the thickness of a coin, said holders having curved notches in their open tops, and a transverse member connecting said holders, substantially as de- 55 scribed.

3. A device for displaying coins and the like, 60 consisting of two short parallel sheet-metal tubes, whose width is the same as the thickness of a coin, said tubes being adapted to receive a coin edgewise, and a transverse member connecting said tubes, substantially as described.

4. A device for supporting a coin or the like 65 and displaying its obverse, reverse and periphery, consisting of a metal holder having parallel sides spaced apart the thickness of the coin, and a flat top provided with an intermediate cut-away portion corresponding with a short arc of the coin, said holder being 70 thus adapted to receive a small portion only of the edge of the coin, and to retain the same by having the edges of the cut-away portion bent inwardly on each side to clamp the beaded rim of said small portion of the coin. 75

In testimony whereof I affix my signature in presence of two witnesses.

LILLIAN C. WHITTLESEY.
